UNITED STATES PATENT OFFICE.

ERNST MUELLER AND OTTO FISCHL, OF ST. LOUIS, MISSOURI.

HEEL-SUPPORT.

1,242,363.

specification of Letters Patent.

Patented Oct. 9, 1917.

Application filed April 8, 1916. Serial No. 88,430.

To all whom it may concern:

Be it known that we, ERNST MUELLER and Otto Fischl, citizens of the United States, residing at the city of St. Louis and State of Missouri, have invented a new and useful Heel-Support, of which the following is a specification.

This invention relates to heel supports and consists in the novel construction hereinafter more fully disclosed.

An object of the invention is to provide an insole adapted to be placed in the rear portion of a shoe, the sole being so formed as to support the heel in a position so that the weight of the body will be thrown upon the ball of the foot to relieve the leg and foot muscles from strain.

Another object of the invention is to provide an insole that will be durable and efficient for the purpose mentioned and which may be worn in a shoe without discomfort to the wearer.

With the above and additional advantages in view which will be readily apparent from the following description, a heel support as hereinafter described and shown in the drawing has been produced.

In the drawing,

Figure 1 is a top view of a heel support embodying the invention.

Fig. 2 is a bottom view of the heel support.

Fig. 3 is an edge view of the heel support.

Fig. 4 is an edge view of the support viewed from the opposite side from the illustration in Fig. 3.

Fig. 5 is a rear edge view of the heel support.

As illustrated in the drawing the device of the present invention includes an upper layer 1 of leather cut to conform to the heel and arch section of a shoe. The forward end of the layer 1 is rounded as indicated at 2, said rounded portion being cut away or beveled as indicated at 3 so that the rounded outer end 2 has a very slight thickness, so that when the support is placed in the shoe the outer edge thereof will extend

to a point back of the ball of the foot at the forward base of the arch. To the layer 1 is attached a retaining strip or layer 4, which is of shorter length and narrower width than the layer 1. The forward edge of the layer 4 is curved inwardly from the outer side edge of the layer 1, as indicated at

5 and curved toward the inner edge of the layer 1 at the rear end as indicated at 6, the intermediate inner edge 7 of the layer 4 lying substantially parallel with and spaced from the inner side edge of the layer 1. The layer 4 is beveled inwardly so that at the line of union of the layers 1 and 4 the edge of the layer 4 is raised only slightly from the bottom of the layer 1. Adjacent to the line of union between the layers 1 and 4 is a row of stitching 8 which passes through both the layers 1 and 4, thereby securing said layers together.

An intermediate layer or insert 9 is placed between the inner surfaces of the layers 1 and 4. The intermediate insert inclines from the outer edge inwardly as will appear by reference to Fig. 5, and is also beveled at its forward end as shown in Fig. 3. The intermediate portion 9 terminates rearward of the forward extremity of the layer 4, so that when the support is placed within a shoe the bottom thereof will lie in a horizontal plane, and the upper surface will incline gradually forwardly and inwardly.

The several layers of which the support is composed are adhesively attached by cement. By constructing the support of the several layers formed as described and cementing said layers together a unitary body is produced which has sufficient solidity to support the foot in proper position and yet has sufficient elasticity to conform to the movement of the foot when worn in the shoe. This results from the fact that the several layers of leather secured together are only slightly compressible in a vertical direction, yet as each layer has flexibility and elasticity on horizontal lines, which lateral elasticity is not in the least destroyed by the cement there is a sufficient lateral yielding and flexing on the horizontal line to conform to the foot movement.

The support, therefore, of the present invention may be worn in the shoe without discomfort to the wearer. Moreover, as the support is formed from united thin layers it is very durable, as there is not sufficient body to any one of the layers to crack when it is flexed by use in the shoe.

As the upper and lower layers are bound together by the row of stitching 8 at the inner edge of the lower layer, there is no danger of lateral displacement of the several layers should the cement become soft when heated by the foot. The row of stitching

also prevents the thin edge of the lower layer from curling backwardly or buckling, so that the surface of the support is kept free from irregularities, and is properly fitted to the foot of the wearer. It will be noted also that the widening of the lower layer at the rearward end provides a full support for the heel, raising the heel sufficiently to incline the foot forwardly thereby throwing the weight from the rearward outer edge of the support forwardly. As the inner forward point of the support terminates just rearward of the ball of the foot, the weight of the body is thrown where it naturally should be, so that all undue strain on the foot and leg muscles is relieved. By thus properly distributing the weight of the body to the forward part of the foot, the comfort of walking is promoted. The support also relieves the exterior surface of the heel of the shoe from undue wear so that by promoting the proper manner of walking the common fault of "running over" of the heels is obviated. The invention may be slightly modified within equivalent limits. It is not desired, therefore, that the invention be limited to the exact construction shown and described, but what is claimed and desired to be secured by Letters Patent, is:—

1. A heel support comprising an upper layer adapted to be placed within the shoe and having a rounded and attenuated forward end, a lower layer of less width than the upper layer having its outer edge matching the outer edge of the upper layer and having an attenuated inner edge parallel with and at a relatively considerable distance from the inner edge of the upper layer, a row of stitching parallel with the inner edge of the lower layer binding the inner edge of the lower layer to the upper layer, an inwardly and forwardly tapering filler piece between the upper and lower layers having its outer edge in alignment with the outer edges of the upper and lower layers and bonding material uniting said layers and filler piece together.
2. A heel support comprising a smooth flat upper layer of leather conforming in

shape to the heel and arch section of a shoe and being adapted to fit within the rearward portion of a shoe, a lower layer having its outer edge formed to match the outer edge of the upper layer and extending inwardly approximately half the width of the upper layer and terminating in an attenuated edge spaced from and approximately parallel with the inner edge of the upper layer, a filler piece interposed between the upper and lower layers having its outer edge conforming substantially to the outer edges of said layers and having its forward end tapering and terminating rearwardly from the forward edge of the lower layer, and having an inward and forward surface slope, and a quantity of bonding material for retaining said layers in bonded union.

3. A heel support comprising a smooth flat upper layer of leather conforming in shape to the heel and arch section of a shoe and being adapted to fit within the rearward portion of a shoe, a lower layer having its outer edge formed to match the outer edge of the upper layer and extending inwardly approximately half the width of the upper layer and terminating in an attenuated edge inwardly from the inner edge of the upper layer, a filler piece interposed between the upper and lower layers and having its outer edge conforming to the outer edges of said layers and having its forward end tapering and terminating rearwardly from the forward edge of the lower layer and also tapering inwardly and having its inner edge spaced from the inner edge of the lower layer, a quantity of bonding material retaining said layers in bonded union, and a row of stitching passing through said upper and lower layers and extending parallel to the inner edge of the lower layer.

In witness whereof, we have signed this specification in the presence of two subscribing witnesses.

ERNST MUELLER.
OTTO FISCHL.
